Primary Examiner — Barbara Fox*Assistant Examiner* — Dana K Weiland(74) *Attorney, Agent, or Firm* — Frost Brown Todd LLC(57) **CLAIM**

The ornamental design for a foot sleeve for stretch device, as shown and described.

DESCRIPTION

FIG. 1 is a front perspective view of a foot sleeve, shown attached to a stretch device, showing our new design; FIG. 2 is a front perspective view of a foot sleeve shown by itself;

FIG. 3 is a front elevation view of the foot sleeve;

FIG. 4 is a rear elevation view of the foot sleeve;

FIG. 5 is a right elevation view of the foot sleeve;

FIG. 6 is a left elevation view of the foot sleeve;

FIG. 7 is a top plan view of the foot sleeve; and,

FIG. 8 is a bottom plan view of the foot sleeve.

The broken lines showing the stretch device are for the purpose of illustrating environmental structure and form no part of the claimed design.

1 Claim, 4 Drawing Sheets(56)
